UNITED STATES PATENT OFFICE.

CHARLES S. ANDERSON, OF MINNEAPOLIS, MINNESOTA.

CYLINDER-BORING MACHINE.

1,152,590.

Specification of Letters Patent.

Patented Sept. 7, 1915.

Application filed March 18, 1914. Serial No. 825,547.

To all whom it may concern:

Be it known that I, CHARLES S. ANDERSON, a citizen of the United States, residing at Minneapolis, in the county of Hennepin and State of Minnesota, have invented certain new and useful Improvements in Cylinder-Boring Machines; and I do hereby declare the following to be a full, clear, and exact description of the invention, such as will 10 enable others skilled in the art to which it appertains to make and use the same.

My invention has for its object to provide an extremely simple and highly efficient boring machine adapted for use to bore out engine cylinders, and to such ends, generally stated, the invention consists of the novel devices and combinations of devices hereinafter described and defined in the claim.

Particularly, my invention has for its object to provide a cylinder boring machine of small cost, for use in repair shops, and which may be operated either by hand or by machine power, and by the use of which, 25 old or used cylinders may be very quickly and cheaply bored out and trued up by a cutting tool, rather than by the use of a grinding machine. In practice, a grinding machine has been found very unsatisfactory 30 for truing up engine cylinders, because the emery or carborundum dust becomes embedded in the minute pores of the cast metal, and subsequently, causes the cylinder to be worn out rapidly.

In the accompanying drawings which illustrate the invention, like characters indicate like parts throughout the several views.

Referring to the drawings: Figure 1 is a view chiefly in side elevation with some 40 parts sectioned, showing the improved boring machine; Fig. 2 is a plan view of the boring machine, some parts being in horizontal section; Fig. 3 is a section taken on the line $x^3 x^3$ on Fig. 1; Fig. 4 is a section 45 taken on the line $x^4 x^4$ on Fig. 1; and Fig. 5 is a section on the line $x^5 x^5$ on Fig. 1.

The numeral 1 indicates a cast bed-plate having suitable bearings 2, 3, 4 and 5. Mounted in the bearings 2, 3 and 4, for both 50 rotary and endwise movements, is a heavy boring shaft 6, the front end of which as shown, is reduced and threaded and detachably holds a tool head 7 that is provided with a radially adjustable cutting tool 8.

The bearing 5 is axially alined with the 55 shaft 6, and detachably held therein, by a set screw 9, is a split or two-part bushing 10.

The numeral 11 indicates a feed shaft that has screw-threaded engagement with and extends through the bushing 10, and is keyed, 60 or otherwise rigidly secured at one end to the adjacent end of the boring shaft 6. The threads on the feed shaft 11 are very fine, and in fact, are of the proper fineness or tread to give the proper advance movement 65 to the tool 8 when the shafts 6 and 11 are given a simultaneous rotation. The said shafts 6 and 11 may be given common rotation, either by hand, or by power. To provide for rotating said shafts by hand, 70 the feed shaft 11 is provided at its outer end with an operating crank 12; and to provide for driving said shafts by machine power, a beveled gear 13 is applied on the shaft 6 between the bearings 3 and 4, and 75 the hub of the said gear 13 is provided with a key 14 that works in a long longitudinal groove 15 of the boring shaft 6. A pinion 16 meshes with the gear 13 and is secured to the inner end of a shaft 17 journaled in a 80 bearing 18 and provided at its outer end with a driving pulley 19. The bearing 18 is shown as rigidly secured to and projecting from the bearing 3.

The front end of the bed-plate or frame 85 1 is planed true vertically, and an alining plate, or face plate, 20 is secured thereto, preferably by bolts 21 and dowel pins 22. This alining plate 20 is provided with a large circular opening 23 that is adapted to 90 receive the end fin y of the engine cylinder y^1 . It is customary to provide engine cylinders with these fins y , but where they are not provided, the cylinders must be otherwise axially alined with the boring shaft 6. 95 The said cylinders are adapted to be secured to the alining plate 20 by bolts, clamps or any of the well known devices used for such purposes.

The use of the improved boring machine 100 is probably obvious, but may be briefly stated as follows: When the cylinder is properly secured on the alining plate, the cutting tool 8 is positioned just outside of the cylinder, ready to enter the same, and 105 then by rotating the shafts 6—11, by hand or by machine power, the cutting tool will be rotated and advanced spirally, so as to pro-

duce the proper boring action. Obviously, the feed movement automatically follows when the shafts 6-11 are rotated, and the rate of feed must, of course, vary proportionate to the speed of rotation. Otherwise stated, each rotation of the cutting tool will advance the same in the cylinder a distance equal to the travel or tread of one thread, or convolution of the feed screw or shaft 11.

10 Shaft 11 is, in effect, an extension of shaft 6.

When the tool has reached its extreme position into or through the cylinder, a quick return thereof and of the shafts 6 and 11, 15 may be accomplished simply by loosening the set screw 9 and removing the two-part threaded bushing 10, so that the said shafts 6 and 11 may be freely drawn outward, or back to starting point.

20 This improved boring machine or tool has been made and successfully used and has been found highly efficient for the purposes had in view. In fact, it has been found that by the use thereof, cylinders may be bored 25 out at a very much less cost than that incurred by the use of grinding machines. Also, the machine is of small cost, that it meets the requirements of small repair

shops, and is highly satisfactory when operated by hand power.

30 What I claim is:

A self-contained boring machine comprising a bed frame having longitudinally spaced axially aligned bearings, a cylinder alining plate secured to one end of said frame and having a cylinder seat located adjacent to one end member of said bearings and axially aligned therewith, a boring shaft mounted for rotary and endwise movements in said bearings and provided with a threaded axially projecting stem, at one end, extended through the bearings at the other end of said frame, said latter bearing having a sectional dismountable internally-threaded bushing normally anchored therein and in 45 engagement with said threaded stem, the said boring shaft having a boring tool at that end which projects through the cylinder seat of said alining plate, and means for rotating said boring shaft.

50 In testimony whereof I affix my signature in presence of two witnesses.

CHARLES S. ANDERSON.
